CLAIM

An ornamental design for a wearable audio recorder with a wearable remote control, as shown and described.

DESCRIPTION

FIG. 1 is a perspective view of a wearable audio recorder with a wearable remote control, showing my new design; FIG. 2 is a front view thereof; FIG. 3 is a rear view thereof; FIG. 4 is a right-side view thereof; FIG. 5 is a left-side view thereof; FIG. 6 is a top view thereof; FIG. 7 is a bottom view thereof; and, FIG. 8 is another perspective view thereof, in which the wearable audio recorder is shown in open clip state and the wearable remote control is separated. Area depicted by line hatch in FIG. 1 and FIG. 2 shows a contrasting texture.
